(57) **CLAIM**

I claim the ornamental design for a display screen with animated graphical user interface, as shown and described.

DESCRIPTION

FIG. 1 is a front view of a display screen with animated graphical user interface showing a first image in the sequence;

FIG. 2 is a front view of a display screen with animated graphical user interface showing a second image in the sequence;

FIG. 3 is a front view of a display screen with animated graphical user interface showing a third image in the sequence

FIG. 4 is a front view of a display screen with animated graphical user interface showing a fourth image in the sequence;

FIG. 5 is a front view of a display screen with animated graphical user interface showing a fifth image in the sequence;

FIG. 6 is a front view of a display screen with animated graphical user interface showing a sixth image in the sequence; and,

FIG. 7 is a front view of a display screen with animated graphical user interface showing a seventh image in the sequence.

The outermost broken line perimeter illustrates a display screen and forms no part of the claimed design. The remaining broken lines illustrate portions of a graphical user interface which form no part of the claimed design.

The appearance of the transitional image sequentially transitions between the images shown in FIGS. 1 to 7. The process or period in which one image transitions to another image forms no part of the claimed design.
